UNITED STATES PATENT OFFICE.

ROBERT DAVID LAMPSON, OF NEW YORK, N. Y., ASSIGNOR TO HIMSELF
AND MAYER MICHAELS, OF NEW YORK, N. Y.

ELECTRIC ADVERTISING DEVICE AND STREET-INDICATOR.

SPECIFICATION forming part of Letters Patent No. 733,053, dated July 7, 1903.

Application filed March 18, 1902. Serial No. 98,777. (No model.)

To all whom it may concern:

Be it known that I, ROBERT DAVID LAMPSON, a subject of the King of Great Britain, residing at New York, in the county and State of New York, have invented certain new and useful Improvements in Electric Advertising Devices and Street-Indicators, of which the following is a specification.

This invention relates to electric advertising devices and street-indicators, and has for its object to provide an improved device of the class described which will possess points of advantage in convenience, effectiveness, and general efficiency.

15 Another object of this invention is to provide an improved device of the class described which will successively present the names of streets or advertisements or other ideas placed in the device.

20 In the drawings, Figure 1 is a front elevation of an indicator embodying my improvements with the front removed. Fig. 2 is a side view of the same on line *yy*, Fig. 1. Fig. 3 is a side view of the same on line *xx*, Fig. 1. Fig. 4 is a diagrammatic view with parts broken away, showing trolley and conductor-rail connections. Fig. 5 is a horizontal cross-section looking downward, taken on the line 25 55, Fig. 3.

30 Corresponding parts in all the figures are denoted by the same reference characters.

Referring to the drawings, 1 designates a casing within which the operative parts of my invention are housed, and which may be 35 of any suitable form to adapt it to the position in which it is to be placed. The casing 1 has a suitable opening 2 in its front, over which a transparent covering 3 may be placed. In the form shown the casing 1 is a rectangular box-like device adapted to be secured above the door at the end of a car. In the upper and lower part of the casing shafts 4 are rotatably mounted transversely of the casing 1. The shafts 4 are provided at one 40 end with a gear 4^a, which meshes with a spring-controlled wheel 4^b, mounted in proximity to the shafts 4 and tending to turn the shafts 4 in opposite directions. The shafts 4 carry spools 5, to which the ends of a strip 6 of flexible material are respectively secured. The strip 6 is provided at suitable intervals 45 with whatever it is desired to display through the opening 2—as, for instance, the names of the streets the car passes or advertisements. On the inside of the strip 6 and extending the 50 whole length of such strip 6 and having its ends likewise secured, respectively, to the spools 5 is a strip 7 of suitable material, preferably steel, which has a series of perforations 7^a along its edges. Mounted transversely of the casing 55 1, near the front thereof and slightly above the opening 2, is a shaft 8, carrying toothed wheels 9, complementary to the perforations 7^a in the strip 7 and adapted to engage said perforations 7^a and move the strip 7, carrying 60 with it the strip 6. The circumference of the wheels 9 is equal to the distance between the centers of the spaces occupied by the matter to be displayed through the opening 2, so that at each revolution of the wheels 9 the strip 6 65 is moved one space. The strip 7 is held in constant engagement with the toothed wheels 9 by a roller 10, placed outside the strip 6, and the toothed wheels 9, the roller 10, and a similar roller 11 placed on the inside of the strip 7 and below the opening 2, serve as guides to hold the strip 6 parallel to the inside of the front wall of the casing 1. Near one end of the shaft 8 a bevel-gear 12 is loosely mounted between two friction-disks 13, one of which is 70 75 fixedly secured on the shaft 8, and the other is slidably mounted on the shaft 8 and provided with means of pressing it against the gear 12, which means are here shown as a spring 14, coiled about the shaft 8 and bearing at one end against the slidably-mounted disk 13 and at the other end against a collar 15, adjustably mounted on the shaft 8. The shaft 8 carries at the end opposite the gear 12 a finger 16. Adjacent to the finger 16 a shaft 75 80 85 90 95 17 is mounted, which carries an escapement-wheel 18, provided with recesses in its perimeter, against the upper or lower surface of which the finger 16 normally rests, according to the direction of its rotation, and a ratchet-wheel 19. Means are provided for permitting the intermittent revolution of the shaft 8. In the form shown such means consist of an electromagnet 20, located in juxtaposition to the ratchet-wheel 19, and the armature 20^a of which carries a pivoted spring-actuated pawl 21, which when the magnet 20 is ener-

gized causes the ratchet-wheel 19 to move one step. This permits the finger 16 to pass through one of the recesses in the perimeter of the escapement-wheel 18 and the shaft 8, carrying the toothed wheels 9, to make one revolution. The electromagnet 20 is connected through suitable electrical connections with a suitable electrical battery (not shown) and an electrical bell 22 and an electrical push-button (not shown) within convenient reach of an operator, who may be the conductor of the car.

A driving-shaft 24 is suitably mounted in the casing 1 and connected with suitable motive power, preferably an electric motor 25, of any of the usual types. The driving-shaft 24 is provided at each end with a bevel-gear 26, one of which meshes with a gear 25^a, carried by the motor 25, and the other with the bevel-gear 12. The motor 25 has a switch (not shown) for reversing the action of said motor 25, which is also placed within reach of such operator.

If desired, the electrical connections connected with the electromagnet 20 and the bell 22 may be conducted to a convenient point adjacent to the overhead trolley-wire or the underground conductor-rail and be operated by a trip 28, placed adjacent to the street-crossings upon said wire and rail and which trip in the form herein shown consists in the case of overhead wire of an arm 29, extending outward from said wire and having the depending end portion adapted to contact with said electrical connections and complete the electrical circuit, and in the case of the conductor-rail of an arm 30, depending from said rail and having an end portion projecting horizontally and adapted to contact with the ends of such electrical connection and complete the circuit.

The operation and advantages of my invention will be readily understood and appreciated.

45 The casing 1 may be secured over the door at the ends of cars or along the sides of such cars over the windows, respectively, as it is to be used to display the names of the streets passed or of advertisements. In either case 50 the features to be displayed are placed upon a strip of flexible material at a suitable distance apart, so that only one at a time will show through the opening 2 and such strip laid upon a perforated metal strip 7, the ends 55 of both of which strips are secured, respectively, to the spools 5, the said strips having previously been passed over the roller 11 and between the toothed wheels 9 and roller 10, which serve as guides to hold that portion of

60 the strip containing the feature to be exhibited parallel with the inner wall of the front of the casing 1. The electric motor 25 is now started and through the driving-shaft 24 revolves the gear 12, which as long as the 65 finger 16 rests against the escapement-wheel 18 turns about the shaft 8, the friction-disks

13 not having friction enough to overcome the resistance offered by the finger 16. When it is desired to change the feature opposite the opening 2, the push-button is pressed, 70 causing the energization of the electromagnet 20 and the movement of the ratchet-wheel 19 one space, during which movement the finger 16 passes through one of the recesses in the perimeter of the escapement-wheel 18, and 75 the finger's resistance being removed the gear 12 rotates the shaft 8 until the finger 16 again comes in contact with the escapement-wheel 18, at which time the shaft 8 will have made one revolution. As soon as the push-button 80 is released the electromagnet 20 is demagnetized and the pawl 21 prevents further movement of the ratchet-wheel 19, so that after one revolution of the shaft 8 the finger 16 is arrested by the escapement-wheel 18. 85 In this situation the shaft 8 will not be turned by the meshed gears 12 and 26, because the tension of the friction-disks is insufficient to overcome the resistance offered by the engagement of the finger 16 and the escapement-wheel 18. 90 When the strip has been wound upon one of the spools 5 to its utmost limit, the motor 25 is reversed in the usual way by the operator and the strip wound upon the other spool, causing the reverse movement of 95 said strip. It will thus be understood that the streets along the route of a car may be easily displayed for the convenience of passengers during the entire passage of the preceding block and that when the end of the route is reached all that is necessary to display the streets in their reverse order is to reverse the motor 25.

In case it is desired to display advertisements the means, such as a clock-movement, 100 for stopping the revolution of the wheels 9 may be arranged to release said wheels at predetermined intervals and the motor 25 may be so connected with the device that when the strip is fully wound upon one of the spools 5 105 the additional bulk of said spool may itself operate a switch to reverse the motor 25.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope 115 of my invention and improvements. I therefore reserve the right to all such variation and modification as properly fall within the scope of my invention and the terms of the following claims.

Having thus described my invention, I claim and desire to secure by Letters Patent—

1. A device of the class described, comprising a casing provided with a sight-opening, rollers mounted in said casing above and below such opening, a strip secured at the ends to said rollers and provided with a perforated

metal backing and on its outer surface with objects to be displayed, a shaft carrying toothed wheels engaging said perforations, and a motor geared to said shaft for intermittently rotating said toothed wheels to bring such objects successively before the sight-opening.

2. A device of the class described, comprising a casing provided with a sight-opening, rollers mounted in said casing above and below such opening, a strip secured at its ends to said rollers and provided with a perforated metal backing and on its outer surface with objects to be displayed, a shaft carrying toothed wheels engaging said perforations, a gear loosely mounted on said shaft between friction-disks carried by said shaft, a driving-shaft carrying a gear connected with the loosely-mounted gear, means for intermittently releasing the toothed-wheel shaft for one revolution, and an electric motor operatively connected with the driving-shaft.

3. In a device of the class described, comprising a casing provided with an opening in front, rollers mounted in said casing above and below said opening, a perforated strip carrying the object to be displayed and secured at its ends to said rollers, a shaft carrying toothed wheels adapted to engage said perforations, and means for operating said shaft, a finger carried by said shaft, an escapement-wheel against the upper or lower surface of which the finger normally rests according to the direction in which the shaft is turned and the perimeter of which is provided with notches for the passage of the finger as the escapement-wheel is moved, a ratchet-wheel on the escapement-wheel shaft, and means for moving said ratchet-wheel step by step to release said finger and permit one revolution of said toothed-wheel shaft.

4. In a device of the class described, comprising a casing provided with an opening in front, rollers mounted in said casing above and below said opening, a perforated strip carrying the object to be displayed and secured at its ends to said rollers, a shaft carrying toothed wheels adapted to engage said perforations, and means for operating said shaft, a finger carried by said shaft, an escapement-wheel against which said finger normally rests, a ratchet-wheel on the escapement-wheel shaft, an electromagnet, an armature controlled by said magnet, a spring-pawl carried by the armature and adapted to move the ratchet-wheel step by step to release the finger and permit one revolution of the toothed-wheel shaft, and means for energizing the magnet.

5. A device of the class described, comprising a casing provided with a sight-opening, rollers mounted in said casing above and below such opening, a strip secured at its ends to said rollers and provided with a perforated metal backing and on its outer surface with objects to be displayed, a shaft carrying toothed wheels engaging said perforations, a

gear loosely mounted on said shaft between friction-disks carried by said shaft, a driving-shaft carrying a gear connected with the 70 loosely-mounted gear, means for intermittently releasing the toothed-wheel shaft for one revolution, and an electric motor operatively connected with the driving-shaft.

6. In a device of the class described, comprising a casing provided with an opening in front, rollers mounted in said casing above and below said opening, a perforated strip carrying the object to be displayed and secured at its ends to said rollers, a shaft carrying toothed wheels adapted to engage said perforations, and means for operating said shaft, a finger carried by said shaft, an escapement-wheel against which said finger normally rests, a ratchet-wheel on the escapement-wheel shaft, and means for moving said ratchet-wheel step by step to release said finger and permit one revolution of said toothed-wheel shaft.

7. In a device of the class described, comprising a casing provided with an opening in front, rollers mounted in said casing above and below said opening, and a strip perforated along its edges and carrying the objects to be displayed and secured at its ends to said rollers, a shaft carrying toothed wheels in engagement with said perforations and having a friction-gear thereon, a motor connected with said friction-gear, and means for intermittently stopping the revolution of said shaft.

8. A device of the class described, comprising a casing provided with an opening in front, rollers mounted in said casing above and below said opening, spring-wheels normally tending to revolve said rollers in opposite directions, a flexible strip provided with a perforated backing and secured at the ends to said rollers and having on its outer surface at predetermined intervals the objects to be displayed, a shaft carrying toothed wheels 110 engaging said perforations, a gear loosely mounted on said shaft, between spring-controlled friction-disks, a motor connected by a train of gears with said loosely-mounted gear, a finger carried by said shaft, an escapement-wheel provided with recesses in its perimeter and against whose surface said finger normally rests, a ratchet-wheel carried by said escapement-wheel shaft, a spring-controlled pawl engaging said ratchet-wheel, an 120 electromagnet connected with said pawl, and means for energizing said magnet to move said ratchet-wheel and release said finger.

9. A device of the class described, comprising a casing provided with an opening in front, 125 rollers mounted in said casing above and below said opening, a perforated strip carrying the objects to be displayed and secured at its ends to said rollers, a shaft carrying toothed wheels engaging said perforations, a finger 130 carried by said shaft, an escapement-wheel against the upper or lower surface of which said finger rests according to the direction in which said shaft is turned and the perimeter

of which is provided with notches for the passage of said finger as said escapement-wheel is moved, means for moving said escapement-wheel to release said finger and permit one revolution of said shaft, and reversible means for operating said shaft when said finger is released.

In testimony whereof I have signed my name in the presence of the subscribing witnesses.

ROBERT DAVID LAMPSON.
